Primary Examiner — Mary Ann Calabrese*Assistant Examiner* — Katelin G Kloberg(74) *Attorney, Agent, or Firm* — ScienBiziP, P.C.(57) **CLAIM**

The ornamental design for a lift table, as shown and described.

DESCRIPTION

FIG. 1 is a front and bottom perspective view of a lift table, showing our design;

FIG. 2 is a rear and bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged partial view of detail 9 taken from FIG. 1; and,

FIG. 10 is an enlarged partial view of detail 10 taken from FIG. 1.

The broken lines depict environmental subject matter that form no part of the claimed design.
